UNITED STATES PATENT OFFICE.

ALFRED D. GOODWIN, OF RIPON, CALIFORNIA.

ANTIFRICTION CLIP FOR MOWERS.

Application filed June 14, 1924. Serial No. 720,001.

To all whom it may concern:

Be it known that I, ALFRED D. GOODWIN, a citizen of the United States, residing at Ripon, county of San Joaquin, State of California, have invented certain new and useful Improvements in Antifriction Clips for Mowers; and I do declare the following to be a full, clear, and exact description of the same, reference being had to the accompanying drawings, and to the characters of reference marked thereon, which form a part of this application.

This invention relates to improvements in the common form of mowing devices used in connection with various kinds of agricultural machinery. Such devices comprise a finger bar carrying the stationary cutters and guards, and a reciprocating knife-bar carrying knife blades, slidably supported on the stationary cutters of the guard fingers. As usually mounted, the knife-bar bears directly against the flat edges of wearing plates fixed on the finger bar, resulting in a severe drag being placed on the driving mechanism and causing rapid wear of the contacting surfaces, making frequent renewal of the wearing plates necessary.

The principal object of my invention is to eliminate the above objectionable features by providing roller bearing means for the knife bar arranged so that there is no wearing contact between the finger and knife bars, and the knife-bar will run very much easier than at present.

Another object is to construct my roller-bearing mounting means in such a way that they take the place of the usual knife clips, and are secured onto the finger bar by using the same bolts as are now used in holding such clips.

My device may be properly considered as an attachment, applicable to all standard mowers without requiring that any structural alterations be made thereto.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a top fragmentary outline of an

ordinary mower structure, showing my improved roller clip applied thereto.

Fig. 2 is a cross section on the line 2—2 of Figure 1.

Fig. 3 is a perspective view of the roller clip, detached.

Referring now more particularly to the characters of reference marked on the drawings, the numeral 1 denotes a finger bar, 65 having forwardly projecting guards 2 on which are the ledger plates or fixed cutters 3. Positioned between the ledger plates and the finger bar is the knife bar 4, having the usual knives 5 secured thereon by rivets 6.

The knives overhang the rear edge of the bar 4 somewhat, certain ones resting on wearing plate 7 mounted on the finger bar at suitably spaced intervals. The parts thus far described are standard, and I do not interfere with the same when applying my attachment thereto.

The latter comprises a plurality of plates 8, one for each of the wearing plates, and having slotted holes 9 to align with the bolt holes in said wearing plates. The same bolts 10 employed in securing the wearing plates and the guards thereunder, to the finger bar, are used in securing the plates 8. The latter are bent upwardly at their rear ends 80 for a certain distance, and are then bent to extend horizontally over and beyond the lower portions 8, as shown at 11. The forward extremities of the upper portions 11 are then bent down as at 12 to engage 90 and form guides for the knives and prevent upward movement thereof, in the same manner as is done by the usual clips, which my attachment displaces.

Between the upper and lower plates 8 and 11 are rollers 13 mounted on pins 14 fixed in the plate members. These pins have slightly projecting heads 15 on the lower ends, which rest on the wearing plates 7, and are of course caused to bear firmly thereagainst when the bolts 10 are drawn tight.

The forward edges of the rollers bear against short tracks 16 fixed on certain ones of the knives 5 by means of rivets 17 passed through the same holes already in the knives and knife bar. The length of these tracks is sufficient to allow of the reciprocation of the knife bar through its usual extent of travel without the rollers leaving said tracks, and they are so disposed that when bearing against the rollers, the adjacent edges of the knife bar and wearing plates are free of each

other. This adjustment may be readily obtained by reason of the fact that the bolt holes 9 in the clip-plates are slotted in that direction which enables the clips to be moved to and from the tracks.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A unitary attachment for mowing machines having a finger bar, a cutter bar, and a bearing member mounted on the cutter bar; including a clip adapted to be secured to the finger bar, and a bearing member contained within the clip and projecting beyond one end thereof to frictionally engage the bearing member on the cutter bar.

2. A unitary attachment for mowing ma-

chines having a finger bar, a cutter bar, and a bearing member mounted on the cutter bar; including a clip adapted to be secured to the finger bar, and a pivoted bearing member mounted in the clip and projecting beyond one end thereof to frictionally engage the bearing member on the cutter bar.

3. A unitary attachment for mowing machines having a finger bar, a cutter bar, and a bearing member mounted on the cutter bar; including a roller contained within the clip and projecting beyond one end thereof to frictionally engage the bearing member on the cutter bar.

4. A unitary attachment for mowing machines having a finger bar, a cutter bar, and a bearing member mounted on the cutter bar; including a U-shaped clip adapted to be secured to the finger bar, a bearing member contained within the clip and projecting beyond one end thereof to frictionally engage the bearing member on the cutter bar; one side of the clip projecting beyond said cutter-bar bearing member and being bent to engage and guide the knives of the cutter bar.

In testimony whereof I affix my signature.
ALFRED D. GOODWIN.
